CARBURETOR

Victor R. Heftler, Grosse Pointe Park, Mich.

Application July 30, 1940, Serial No. 348,431

6 Claims. (CL. 261—69)

It is an object of this invention to provide a carburetor of the double Venturi type having a mixture conduit of such a design as to permit accurate machining of the air swept surfaces of said conduit.

It is a further object of this invention to provide in a downdraft carburetor an idling by-pass so shaped as to hold an excess charge of fuel for use in starting the engine, or upon the engine resuming normal operation after deceleration.

It is a further object of this invention to provide a sensitive device for cutting off the supply of fuel when the engine is decelerating.

It is a further object of this invention to provide an improved accelerating pump.

Fig. 1 is an elevation, viewed from the lower side of Fig. 2.

Fig. 2 is a top plan view, with one half of the cover removed.

Fig. 3 is an elevation, viewed from the top side of Fig. 2, with some parts cut away.

Fig. 4 is an elevation, viewed from the right side of Fig. 2 with some portions in cross-section along parallel lines 4a, 4b, 4c and 4d of Fig. 2.

Fig. 5 is a partial cross-section along line 5—5 of Fig. 2 and viewed in the same direction as Fig. 9.

Fig. 6 is a partial cross-section along line 6—6 of Fig. 2.

Fig. 7 is a diagrammatic scheme illustrating the complete idling system.

This invention is described as applied to a down draft carburetor, which comprises a downwardly discharging throttle housing member 21, provided with a flange 22 for attachment to an engine manifold (not shown) in the well known manner. The throttle housing member 21 supports a mixing chamber body member 23, which, in turn, supports a cover member 24, these three main parts being suitably fastened to one another, by screws 25 for instance. A heat insulating gasket 52 is preferably inserted between the throttle housing member 21 and the mixing chamber body member 23.

The entire air supply enters through a conduit 26 in the cover member 24 (Fig. 1) controlled by a choke valve 27 mounted on shaft 28 to which is fastened choke lever 29, to be actuated in any one of the ways now current and well known in the art. Conduit 26 registers with conduit 30 in the mixing chamber body member 23, which leads to conduit 31 in the throttle housing member 21. A throttle valve 32, mounted on shaft 33, controls conduit 31 to restrict more or less the free passage of mixture to the engine associated with

the carburetor. The means used to rotate the throttle are not shown and may consist, as in most automobiles, of a lever fastened to the throttle shaft and actuated by the driver according to his wishes for more or less speed or power.

The movement of the throttle is limited by means of stop lever 34, fastened on shaft 33, and provided with two lugs 35 and 36. When the throttle is opened wide, lug 35 comes in contact with stop pin 37, which may be cast integral with the throttle housing member 21. To control the so-called closed position of the throttle, a screw 38 is threaded in lug 36, its end being adapted to contact a combined yielding stop and valve 39.

10 The word "closed," although used universally in carburetor parlance, is not strictly accurate: if the throttle were closed so tightly that no air could pass, the engine would stall; to avoid this, it is customary to prevent the complete closure of the throttle so as to leave, between the edge of the throttle and the bore in throttle housing member 21, a narrow opening just sufficient to admit enough mixture of fuel and air to keep the engine running at slow speed, or "idling," as it is called. The amount of mixture necessary for idling varies with the engine, and, on a given engine, varies with its condition, therefore, the position of the throttle for idling should be adjustable, as is done by means of screw 38.

15 Formed in the mixing chamber body member 23 is a constant level fuel chamber 62. A fuel supply pipe (not shown) may be connected to the threaded inlet 63, leading to a needle valve which is actuated, in the well known manner, by a level sensitive device, in this case a pair of floats 35 symmetrically located with reference to line 4—4 of Fig. 2, where one of the floats is shown in plan at 65, the other 65a being shown in elevation in Fig. 3. The parts are so made and proportioned that liquid fuel will fill the chamber to the level of line L—L in Figs. 3 and 6.

20 A calibrated orifice 67 allows fuel to flow into chamber 68 and hence, through main jet tube 69, to the annulus 60. Shank 45 of the second Venturi holder is drilled at 70 to a diameter larger than the outside of main jet tube 69, thus leaving a tubular passage 71 around said main jet tube. The diameter of shank 45 is reduced, below shoulder 46, to a diameter smaller than that of hole 72, so that there is formed another tubular passage 71a, concentric with 71, and leading from chamber 73. A main well 74 (Fig. 3) is drilled vertically, somewhat off the vertical plane 4—4 of Fig. 2, but close enough thereto to intersect hole 72 at 75, where it connects with tubular pas-

sage 71a. Well 74 is opened to the air in the top of the fuel chamber, preferably through a calibrated opening 76 in removable main vent piece 77. At some distance below the fuel level L—L and in plane 6—6 of Fig. 2, a communicating passage 78 (Fig. 6) is drilled, intersecting main well 74, and opening into chamber 73 at 79. A threaded member 89, whose slotted head is visible in Figs. 2 and 3, is provided with a calibrated orifice to afford a controlled fuel feed from the fuel chamber 62 to the passage 78. This member 89 is diagrammatically indicated on Fig. 6, although, strictly speaking, it is not visible on this cross-section as it lies entirely in front of the plane of the figure.

The suction obtaining in annulus 60 draws solid fuel through main jet tube 69 and, through tubular passage 71 and chamber 73, will draw air from main well 74 to form an emulsion with fuel drawn through the calibrated orifice of piece 80. The man skilled in the art will readily recognize the method of obtaining a correct mixture by the combining of two fuel feeds as the well known one disclosed in U. S. Patent 907,953.

When the throttle is in "idling" position, the suction in the second venturi becomes insufficient to lift any fuel up to the annulus 60, but an "idling by-pass" is resorted to supply fuel to the engine. This idling by-pass takes the form of an inverted U, with one branch extending from a calibrated fuel orifice below the fuel level to an horizontal connection above said fuel level with the other branch which leads downwardly to the proximity of the throttle. The drilled hole 78 is adapted to receive and to be closed by the end of idling supply piece 81. A calibrated hole 84 is drilled in the tip of said piece 81, which is also cross-drilled, so that fuel, limitedly supplied through calibration 84, may reach the tubular passage 85 between piece 81 and hole 82. Hole 82 is plugged against leakage by plug 83. Vertical hole 86, Fig. 5, intersects this tubular passage to bring into it air from air conduit 30 through hole 87, the effective area of which may be regulated by means of the idling adjusting screw 88. The top of hole 86 is covered by the base of cover member 24 and is closed thereby. The idling by-pass has its beginning or origin at the tubular passage 85, close to the calibrated hole 84 which measures fuel thereto and well below the level L—L of the fuel. It is made up of vertical hole 89, horizontal connecting hole 90 and hole 91 leading downwards and connecting with passage 92 which opens into chamber 93, connected with the main mixture passage through ports 94 and 95 bestriding the edge of the throttle when the latter is in closed position. When the engine is at rest, idling well 86 is filled with solid fuel up to line L—L, and so is channel 89. Upon starting the engine with the throttle in idling position, this solid fuel will be drawn through the idling passages towards chamber 93 before normal idle feed is established. After the first few strokes of the engines, air measured at 87 comes down well 86 to mix with the fuel passing through calibration 84, forming an emulsion which flows through the inverted U tube 89, 90, 91 towards chamber 93. This initial charge of pure fuel standing in 86 and 89 is very useful in starting. Another advantage is found in the rapidity with which the idling channels will resume their normal working upon returning to idling speed: When the engine is running with the throttle opened well beyond

the idling position, the fuel flowing through the calibrated orifice in piece 80 will be urged away from the idling channels towards annular passage 71 and the second venturi and there may be a reverse flow of air from main conduit 31 through holes 94 and 95 into chamber 93, through the idling channels into channel 78, because the suction at the double venturi is greater than the suction ports 94 and 95. If then the throttle be suddenly closed and the load disconnected, as when the clutch of an automobile is disengaged, the motor will slow down rapidly and will stall unless the idling by-pass resumes its function quickly enough. Immediately as the throttle is closed, the suction at the main venturi drops so low that no fuel is delivered at that point, but the high manifold suction is transmitted to passage 92 and air, entering at 87, flows at once through the idling by-pass. As soon as fuel from calibrated hole 84 meets this air stream, it will be picked up by it and carried to the engine. By admitting air into the idling by-pass at a point close to said by-pass beginning, the time necessary to resume normal idling is reduced to a minimum, and stalling from this cause prevented.

If the throttle is closed from a half open position, for instance, the inertia of the engine and of its load prevents its speed from decreasing at once to the idling speed, so that, during this deceleration period, the suction in chamber 93 is abnormally high, which results in an increased pull on the fuel supply at idling calibration 84 so that too rich a mixture is delivered to the engine, and that at a time when no power is required. Such excess fuel produces obnoxious fumes and is wasted; this happens when an automobile coasts down to a stop or downhill. To obviate this defect, it has been proposed to utilise the abnormally high suction to operate a valve admitting air into the idling channels. See the French patent to Waseige No. 545,073, Fig. 1. If this admission of air is large enough, it will satisfy the suction in the idling by-pass, and no fuel will be fed therethrough. I have found that, on an inch and a quarter carburetor, it was necessary to use an air admission of $\frac{7}{4}$ ths of an inch to completely prevent the feeding of fuel. The present invention comprises certain improvements on this principle to make the operation positive and rapid and also to prevent this operation unless the throttle is in the idling position. It is necessary to open the hole that admits air into the idling channels completely as soon as the need for it arises, otherwise, if the parts were to remain for an appreciable length of time in an intermediate position, the idling channels would continue to feed a diminished amount of fuel and a weak mixture would be fed to the engine, with the well known drawbacks of a weak and slow burning mixture, such as backfire and pitting of the intake valves. It must be recognized that the "normal" vacuum in the manifold, or downstream of the throttle, and here "normal" means the vacuum when the engine is driving the car and not decelerating, does not decrease at once upon opening the throttle. Tests on a particular car have shown a vacuum of 18" of mercury at 10 miles per hour, rising to a maximum of 19" at 25 miles per hour to decrease again to 18" at 37 miles and to 12" at 65. If the admission of air was dependent only on manifold vacuum and was regulated to occur for a vacuum of say 18 $\frac{1}{2}$ ", one half inch more than

the normal idling vacuum, it would also occur when the car is running normally at speeds between 15 and 35 miles per hour. This would upset the carburetion at a critical time in the operation of the carburetor when fuel feeding is being transferred progressively from the idling system to the double venturi.

Adapted to slide in bore 97 machined in the throttle housing body member 21 is the operating piston 98 (Fig. 3), which is urged upwards by the spring 99. The lower portion of bore 97 communicates through hole 100 with the main conduit 31 below the throttle so that the vacuum that obtains there would pull the piston downwards against the spring, were it not for the fact that this vacuum is also impressed on the top of the piston through the small aperture 101. At right angle to this bore 97, and shown on Fig. 4, is a pilot piston 102, slideable in bore 103, said bore being closed on the right by plug 104 forming a stop for the pointed head of the piston and closed at the other end by gland 105, in which is threaded screw 106 for adjusting the tension of spring 107. The head of this piston is exposed to atmospheric pressure through channels 96 and 109. A passage 110 leads from the space above the head of the operating piston 98 into the bore 103, close to the head of pilot piston 102, but covered thereby when the carburetor is at rest. In the diagram of Fig. 7, the two bores 97 of the operating piston and 103 of the pilot piston are of necessity shown with their axes in the same plane. In the working construction, bore 97 is vertical, as in the diagram and is shown in section in Fig. 3, but bore 103 is horizontal and perpendicular to the plane of Fig. 3, its axis being at the center of plug 104 which closes it. In the diagram, passage 110 is radial to both bores, in the construction illustrated, it is radial to bore 97 of the operating piston and tangent to the bore 103 of the pilot piston, so that, due to the elongated shape of the opening made by passage 110 into bore 103, it will not be necessary that piston 102, acting like a slide valve, uncovers said opening completely to obtain an effective communication between the two bores as the diameter of passage 110 permits. With the parts in the position shown, piston 102 closes passage 110, and atmospheric pressure is not transmitted therethrough to the space above the head of operating piston 98. On the contrary, this space is subjected, through small aperture 101, to the same vacuum as is impressed upon the underside of piston 98. Because of this equalization of the pressures on both sides of the piston, spring 99 need not be very strong to hold it in and return it to its position.

The combined stop and valve 39 (Fig. 4) is provided with two conical surfaces 112 and 113 adapted to co-operate with corresponding valve seats in the stop housing 114 cast integral with the throttle housing body 21. A channel 115 connects the pilot piston bore 103 with chamber 116 located between the two valve seats. Channel 117 leads from the down stream side of the throttle to the space in stop housing 114 adjacent the seat for valve surface 112 and channel 118 leads from the upstream side of the throttle to the space adjacent the seat for valve surface 113. When the throttle is in the idling position, as shown, the throttle stop screw 38 holds valve surface 112 off its seat so that the manifold vacuum, taken downstream of the throttle through 117, is impressed through 115

to the back of the pilot piston. Spring 107 is adjusted so as to prevent any movement of the pilot piston 102 as long as the manifold vacuum does not exceed the normal idling vacuum. During deceleration, the vacuum is higher than normal, and, provided the throttle be closed and valve 39 in position to open channel 115 to the manifold vacuum, the pilot piston 102 will move to the left and uncover hole 110, whereupon the upper side of piston 98 will be subjected to nearly atmospheric pressure transmitted through 110, 109 and 96, thus destroying the balance between the pressures above and below the piston. The suction below the piston will pull it downwards to the limit of its travel because of the weakness of spring 99. In this movement the groove 111 of the operating piston comes into registration with hole 96, so that air is admitted into chamber 93, thus cutting out the suction on the idling channels so that no fuel is delivered to the engine.

Aperture 101 need not be over $\frac{1}{64}$ th of an inch to transmit the vacuum from one side of the piston 98 to the other; assuming that passage 110 is of the same diameter, its flow capacity will be nearly equal to that of aperture 101, so that, when said passage 110 is opened to atmospheric pressure, the vacuum above piston 98 will be reduced to approximately one half of the vacuum below it. Assuming that spring is so proportioned and adjusted as to begin to open passage 110 when the manifold vacuum reaches $18\frac{1}{2}$ inches of mercury and that the rate of said spring is such that the passage will be fully opened for an increase in vacuum of one half inch, the full opening of this passage will cause a decrease of $9\frac{1}{2}$ inches in the vacuum above piston 98, which will then move downwards a great deal farther than would be the case if it were subjected directly and solely to the manifold vacuum on one side and to atmospheric pressure on the other.

Upon reopening of the throttle, the valve 39 moves to the right, the space at the left of the pilot piston is no longer connected to the downstream side of the throttle, but to the upstream side, through channel 118, where the suction is much lower. The opening of this connection breaks the vacuum so that the spring 107 can force the pilot piston back to its initial position whereupon operating piston 98 is also returned to normal position and normal idling is resumed. During the deceleration, fuel has accumulated in the idling well 86 up to the line L-L and in channel 89 up to a slightly higher level; this small charge of excess fuel is very useful in avoiding any hesitation when normal running is resumed.

It is clear that some other form of suction operated device capable of opening at atmospheric vent could be used, as a pilot valve, in place of the structure described, which is only my preferred form. I base this preference upon the fact that in this slide type of valve the opening and the closing of aperture 110 will occur for the same value of the suction. In other words, if, as assumed earlier, spring 107 is so set that the piston 102 will begin to uncover passage 110 when the increasing suction reaches $18\frac{1}{2}$ inches of mercury upon decelerating, then, when the speed has decreased to such an extent that the suction reaches the same value of $18\frac{1}{2}$ inches on the way down towards normal, the pilot piston will close passage 110 so as to cause normal operation to be resumed. In other types

of valves responsive to suction and often employed in carburetors, there is a difference between the values of the suction for which it opens and for which it closes. In such a case, in order to insure that normal operation will resume for 18½" of suction, it might be necessary to set the spring so that 20" of suction needs to be reached before the valve opens to cause "degassing" to take place. In other words, the degassing would have to be delayed to insure that the "regassing" be brought about before the motor speed drops too low.

I claim:

1. In a carburetor, a main air conduit, an idling by-pass discharging into said conduit, an operating valve normally under the influence of manifold vacuum on both sides thereof, means opened by said valve to admit air into said idling by-pass, and means to admit air on one side of said valve to cause its operation.

2. In a carburetor, a main air conduit, a throttle therein, an idling by-pass discharging into said conduit, an operating valve normally under the influence of manifold vacuum on both sides thereof, means opened by said valve to admit air into said idling by-pass, a pilot valve, throttle and vacuum controlled means to operate said pilot valve, and means operated thereby to admit air on one side of said operating valve to cause its operation.

3. In a downdraft carburetor, a constant level fuel supply chamber, a main mixture conduit, a throttle therein, a main fuel feeding system, an idling by-pass having its origin below the level of the fuel at the main fuel feeding system and adapted to draw fuel therefrom and leading into said mixture conduit in proximity to the

throttle, said idling by-pass being of inverted U shape, and means to admit air into said by-pass in close proximity to its origin.

4. In a carburetor, a main air conduit, a throttle therein, an idling by-pass discharging into said conduit, an operating valve normally under the influence of manifold vacuum on both sides thereof, means opened by said valve to admit air into said idling by-pass, a valve chamber, a vacuum controlled pilot valve therein and a port in said valve chamber communicating with one side of said operating valve and normally covered by said pilot valve.

5. In a carburetor, a main air conduit, a throttle therein, an idling by-pass discharging into said main air conduit, an operating valve constantly under the influence of the manifold vacuum on one side, a restricted vacuum connection to the other side of said valve, means opened by said valve to admit air into said idling by-pass, a valve chamber, a vacuum controlled valve therein and a port in the wall of said valve chamber communicating with the second mentioned side of the operating valve to admit air thereto and normally covered by said second mentioned valve.

6. In a carburetor, a main air conduit, a throttle therein, an idling by-pass discharging into said conduit, an operating valve normally under the influence of manifold suction on both sides thereof, means opened by said valve to admit air into said idling by-pass, a pilot valve under the influence of said manifold suction and means opened thereby to admit air to one side of said operating valve to cause its operation.

VICTOR R. HEFTLER.
